OR D 14,492

No. 14,492

DEC 18, 1883

UNITED STATES PATENT OFFICE.

H. CLAY BASCOM AND CYRUS A. HODGES, OF TROY, N. Y., ASSIGNEES TO N. S. VEDDER PATTERN WORKS, BASCOM, GALBRAITH & CO., OF SAME PLACE.

DESIGN FOR A GLOBE STOVE.

SPECIFICATION forming part of Design No. 14,492, dated December 18, 1883.

Application filed November 7, 1883. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Globe Stoves, of which the following is a specification, reference being had to the accompanying cut, print, or engraving, representing our said new design.

The design for the fire-door A consists of the compound ornament *a*, shaped and arranged upon the surface *b* above and between the circular light-openings *e*, as shown in the aforesaid print.

The design for the casting B consists of the ornaments *d* and *e*, shaped and arranged alternately in a row upon and along the upper portion of the dome-form surface *f*, as shown in the aforesaid cut.

The design for the fender C consists of the peculiar open-work ornamentation, *g*, shaped and arranged between and in combination with the wide convexly and downwardly curved outer band, *h*, and the narrow inner band, *i*, as represented in the aforesaid engraving.

The design for the top plate, D, of the base-section consists of the inner curved ornaments, *j*, and the outer corner ornaments, *k*, shaped and arranged together on said plate as shown in the aforesaid cut.

The design for the side plate, E, of the base-section consists of the corner parts, *l*, and the three panel-surfaces *m n o*, of gradually-de-

creasing extent, all shaped and arranged as shown in the aforesaid print.

The design for the legs consists of the ornaments *p* on the upper part, *q*, and the ornament *r* on the lower part, *s*, all shaped and arranged as shown in the aforesaid engraving.

We claim as our invention—

1. The design for the fire-door A, consisting of the parts *a b c*, shaped and combined as shown and described.

2. The design for the dome-casting B, consisting of the parts *d e f*, shaped, arranged, and combined as shown and described.

3. The design for the fender C, consisting of the peculiar open-work ornamentation, *g*, between and in combination with the bands *h* and *i*, all shaped and arranged as shown.

4. The design for the top plate, D, of the base-section, composed of the ornaments *j k*, shaped and arranged as shown and described.

5. The design for the side plate, E, of the base-section, composed of the parts *l m n o*, shaped and arranged as shown and described.

6. The design for the legs, composed of the parts *p q* and *r s*, as shown and described.

In testimony whereof we hereunto set our hands, in the presence of two subscribing witnesses, this 5th day of November, 1883.

H. CLAY BASCOM.
CYRUS A. HODGES.

Witnesses:

CHARLES H. BENEDICT,
AUSTIN F. PARK.
